UNITED STATES PATENT OFFICE.

EDWARD P. FREDERICK, OF ST. LOUIS, MISSOURI.

ROPE.

1,009,030.

Specification of Letters Patent. Patented Nov. 14, 1911.

Application filed February 6, 1911. Serial No. 606,756.

To all whom it may concern:

Be it known that I, EDWARD P. FREDERICK, a citizen of the United States, residing at the city of St. Louis, State of Missouri, have 5 invented certain new and useful Improvements in Ropes, of which the following is a specification, reference being had therein to the accompanying drawings.

This invention consists of a compound 10 rope or cable. In forming same a new arrangement of the units or component parts is utilized by which greater pliability and increased strength are secured. As thus constructed, this rope has been found of 15 especial serviceability and durability in work on the Panama Canal in connection with ballast unloaders and in the work of dredging, both which uses require ropes of maximum strength and pliability.

20 In the drawings forming part of this specification, in which like numbers of reference denote like parts wherever they occur, Figure 1 is an elevation of a section of this improved rope or cable; Fig. 2 is a 25 longitudinal sectional view exhibiting the relation of the external members to the grooves or interstices between the internal members; and Fig. 3 is a transverse section through a rope or cable exhibiting, also, the 30 relation of said external members to the internal members.

For the sake of perspicuity, distinction will hereinafter be made between the use of the terms wires, strands, ropes, and cables. 35 In the nomenclature of this description, 1 denotes a wire. A group of wires 1 composes a strand 2. The structure as a whole will hereinafter be termed a compound rope or cable. It has heretofore been customary 40 to form cables of this general character with a core composed of members having their "lay" in one direction and the external members with their "lay" in a different direction. Otherwise stated, the practice in 45 the past has been to disregard divergence in the "lay" of the outer and inner members. The result has been great variety and conflict in the "lay" of the wires of the core and of the external units or members combined therewith to form a rope or cable.

50 In such a structure, members crossing each other at a right angle, or other abrupt angle, abrade each other, and thereby weaken the rope or cable. This drawback is obviated in 55 the present invention by making the "lay" uniformly in the same direction, as shown

in the drawings. Furthermore, due to this uniformity of "lay", it is possible to use strands having larger wires, and thus the maximum strength of the rope or cable is 60 increased. Thus, the present invention increases the strength of a rope or cable in, at least, two respects.

A hemp rope 3, or a wire, may be used to form the center member for the core 4, 65 around which the strands 2 that form the outer layer are wound like a sheath. Interstices or grooves 5 are formed between the strands 2 that form the core 4, said core being composed of a plurality of strands 2 70 formed of wires 1. These interstices receive their shape and direction from the direction of the "lay" of the strands 2 forming said core.

The main feature of the present invention 75 consists in imparting to the strands 2 forming the sheath or outside layer of the rope or cable the same "lay" as that of the strands 2 forming the core 4 and, furthermore, in locating the strands 2 composing 80 said sheath or outer layer in the interstices or grooves 5 of the core 4. By reason of the strands 2 of the outer layer or sheath of the rope or cable lying in said interstices or grooves located between the strands 2 forming the core 4, abrasion of both the inner and the outer members is prevented, and it is possible to make a much more compact body than where the "lay" of the external members is across, instead of in, said interstices. 85 In this way, with less circumference, greater strength will be obtained than in the old-style ropes or cables in which, in the first place, the "lay" of the outer and inner members was not made uniform, and, in the 95 second place, the members forming the outer layer were not definitely laid in the grooves between the inner members. Moreover, the flexibility of the rope or cable as a whole is enhanced by all the members having the same "lay," as, thereby, they do not bind 100 upon each other.

It will be observed that while interstices 5 are formed on the outside of the core 4 between the strands 2 forming said core, interstices 6 are formed on the inner side of the external sheath layer, and, by reason of the location of the strands 2 of the outer layer in the interstices 5 of the core 4, the strands 2 of said core lie in the interstices 6 of the outer layer, the interstices 5 and 6 being thus arranged in staggered relation to 105 110

each other, by reason whereof the structure as a whole is, when completed, much more closely bound together. The chief advantages of this formation reside in preventing the wires 1 from creeping or twisting out of their places, when the rope or cable is placed in working service, and thereby obtaining a greater amount of natural wear during the working life thereof, and, also, in producing 10 a rope or cable having a greater adaptability to bending stresses and a greater ultimate tensile or breaking strength than is obtained in a rope or cable of ordinary type or a compound rope or cable composed of strands which do not lie in the interstices of the core.

Having thus described my said invention, what I claim and desire to secure by Letters-Patent is:

20 1. A compound rope or cable comprising a core consisting of a series of spirally-wound strands, each pair of which has an interstice therebetween, and a sheath incasing said core and consisting of a series of strands wound spirally around the same, each pair of sheath strands having an interstice therebetween, said sheath strands having exactly the same lay as the core strands and lying directly in the interstices between

said core strands, and the core strands, in turn, lying exactly in the interstices between 30 the sheath strands, each strand of said core and of said sheath being composed of a series of spirally-wound wires.

2. A compound rope or cable comprising a center member, a core incasing said center member and consisting of a series of strands wound spirally therearound, each pair of adjacent strands having an interstice produced therebetween, and a sheath incasing said core and consisting of a series of 40 strands wound spirally around the same, each pair of sheath strands having an interstice therebetween, said sheath strands having exactly the same lay as the core strands and lying directly in the interstices between 45 said core strands, and the core strands, in turn, lying exactly in the interstices between the sheath strands, each strand of said core and of said sheath being composed of a series of spirally-wound wires. 50

In testimony whereof I hereunto affix my signature in the presence of two witnesses.

EDWARD P. FREDERICK.
